UNITED STATES PATENT OFFICE.

JOHN J. HAGGENJOS, OF ST. LOUIS, MISSOURI.

DESIGN FOR AN AUTOMOBILE STEP PLATE.

Application filed July 27, 1922. Serial No. 3,225. Term of patent 7 years.

To all whom it may concern:

Be it known that I, JOHN J. HAGGENJOS, a citizen of the United States, and resident of St. Louis, State of Missouri, have invented a new, original and ornamental Design for an Automobile Step Plate, of which the following is a description:—

Reference being had to the accompanying drawing, forming a part thereof.

Figure 1, is a top plan view of a step plate embodying my design.

Fig. 2, is a sectional view taken on the line 2—2 of Fig. 1.

Fig. 3, is a sectional view taken on the line 3—3 of Fig. 1.

I claim the original design of an automobile step plate, as shown.

JOHN J. HAGGENJOS.
